CLAIM

The ornamental design for a Christmas light holder, as shown and described.

DESCRIPTION

FIG. 1 is a right side elevational view of a Christmas light holder showing one embodiment of my new design, the opposite side being a mirror image;
 FIG. 2 is a bottom plan view thereof;
 FIG. 3 is a top, left and perspective view thereof; and
 FIG. 4 is a rear elevational view thereof;
 FIG. 5 is a right side elevational view of a Christmas light holder showing an alternative embodiment of my new design, the opposite side being a mirror image;
 FIG. 6 is a bottom plan view thereof;
 FIG. 7 is a rear elevational view thereof; and,
 FIG. 8 is a top, left and perspective view thereof.
